UNITED STATES PATENT OFFICE.

CHARLES W. STUART, OF NEWARK, NEW YORK.

HOE OR WEEDEER.

SPECIFICATION forming part of Letters Patent No. 790,760, dated May 23, 1905.

Application filed March 22, 1904. Serial No. 199,334.

To all whom it may concern:

Be it known that I, CHARLES W. STUART, a citizen of the United States of America, residing in Newark, in the county of Wayne 5 and State of New York, have invented a certain new and useful Improvement in Hoes or Weeders, of which the following is a true and exact description, reference being had to the accompanying drawings, which form a part 10 thereof.

My invention relates to the construction of hoes or weeders, particularly to the sort of hoe known as a "hand-hoe," and has for its 15 object to provide a simple, inexpensive, and efficient tool of this kind, the principal feature of my invention consisting in the particular construction by which the hoe-blade is made reversible.

Reference being had to the drawings, which 20 illustrate my hand-hoe in what I consider to be its most simple and desirable construction, Figure 1 is a perspective view of the tool; Fig. 2, a side elevation thereof; Fig. 3, a plan view thereof, and Fig. 4 a sectional view 25 through the blade on the line 4-4 of Fig. 3.

A indicates the grip or handle, to which is secured in the usual manner the tang B of a holder B', extending at an angle to the tang and provided on each side with sockets, (in- 30 dicated at B² B².)

C is the blade of the hoe or weeder, formed with sharp cutting edges (indicated at C' C') on both edges and having extending from

its ends straps C² C², which terminate in shanks or socket-pieces C³ C³, which are adapted to 35 fit in the sockets B² B² of the holder B', the removable parts being held in position by a nut and bolt, (indicated at D D').

It will be seen that my tool is of the simplest and most inexpensive construction, thoroughly well adapted for the uses to which such tools are put, and has the particular advantage of having a reversible blade which can be turned to bring either cutting edge 40 into operative position with little or no 45 trouble.

Having now described my invention, what I claim as new, and desire to secure by Letters Patent, is—

A hoe having a reversible double-edged 50 blade C, with straps C², C², extending from each end thereof and terminating in shanks C³, C³, in combination with a holder B', having sockets B², B², in its opposite sides adapted to receive the shanks C³, C³, of the blade, 55 said holder B', having an angularly-extending handle-tang B, the reversible blade and straps being symmetrical so as to form with the holder a tool of substantially similar shape in either of its reversible attachments 60 to the holder.

CHARLES W. STUART.
